ROLF HARALD HULT, OF HYLTEBRUK, SWEDEN.

METHOD OF BOILING INDIRECTLY.

1,337,704.

Specification of Letters Patent. Patented Apr. 20, 1920.

Application filed October 24, 1917. Serial No. 198,358.

To all whom it may concern:

Be it known that I, ROLF HARALD HULT, citizen of Finland, residing at Hyltebruk, in the Kingdom of Sweden, have invented 5 new and useful Improvements in Methods of Boiling Indirectly; and I do hereby declare the following to be a full, clear, and exact description of the same.

My present invention has for its object a 10 method of boiling indirectly by steam, said method being especially adapted to be used in boiling or cooking wood or other material containing cellulose according to the sulfite method. The purpose of my present in- 15 vention is to obtain a high economy of heat in the boiling operation, and, consequently, to save fuel.

The indirect boiling of a liquid by means 20 of steam is generally executed, as is well known to those skilled in the art, by leading superheated or saturated steam through one or more metallic coils or tubes submerged in the liquid, the steam thereby giving off its heat to the liquid. The economy of such 25 a method evidently depends on the quantity of heat given off to the liquid by the steam when passing through the coils or tubes, and a measure of the same is the difference of temperature between the incoming and the 30 escaping steam, and water of condensation.

In the indirect boiling by steam, especially 35 at temperatures above the boiling point, one can distinguish two different periods, namely a first period, during which the temperature of the liquid is raised from the ordinary temperature to or nearly to the boiling point, and a second period, during which the temperature is maintained at the boiling point or raised above the same.

40 During the first period the consumption of steam is highest and the condensation in the coils is most complete. The economy of heat during this period is, even in the methods of heating employed hitherto, relatively good. During the second period, on 45 the contrary, the economy has been very bad in the method employed hitherto, this being due to the fact that the heat of the steam, which has hitherto in each boiler been led 50 the same way as during the first period, is utilized less completely and the condensation is less complete.

The principal object of my present invention now is the obtaining of a high economy 55 of heat also during the second period which is rendered possible thereby that the

steam, if wanted together with the water of condensation, is within one and the same boiler led a longer way through the liquid, so that the steam may act upon the liquid 60 for a longer time and more completely deliver its heat to the same.

Another object of my invention consists in applying said method to the sulfite cellulose method so that during the first period 65 (when the temperature is raised from ordinary temperature to about 100° to 105° C.) the steam is led through the coils or tubes being then in the ordinary manner coupled parallelly, and then during the second period 70 of the boiling operation (generally between about 105° to about 138° C. or more) the coils or tubes are coupled in series two and two, three and three etc., and the steam led through the coils or tubes thus coupled together in series.

Another feature of my invention consists therein that, during the second period, the main valve of the outlet conduit for the escaping steam is throttled to a suitable degree for increasing the favorable action of the method.

Other features will be rendered clear in the following description describing as an example the application of the invention in 85 boiling wood according to the sulfite cellulose method, reference being had to the accompanying drawings. Figure 1 schematically illustrates the ordinary arrangement of the heating coils in a cellulose boiler. 90 Fig. 2 shows an arrangement of the same according to the present invention.

Fig. 3 illustrates an arrangement which permits three or more coils to be connected in series.

Fig. 4 illustrates a modification, the showing of the coils being omitted.

Fig. 5 illustrates a form employing few valves.

Fig. 6 illustrates a form having single 100 inlet and outlet valves.

In the indirect boiling of sulfite cellulose superheated or saturated steam, mixed if wanted with water of condensation, is led through coils of lead or copper located in 105 the lower part of the boiler. These coils have hitherto generally consisted of a number of independent coils arranged in the manner indicated by Fig. 1. The coils, generally four to six, are designated by A, B, C, 110 D and E. One end of each coil is connected with the main supply conduit of steam F

by connecting tubes a , b , c , d and e respectively. The opposite ends of the coils are connected with the main conduit G for escaping steam by means of the connecting tubes a^1 , b^1 , c^1 , d^1 and e^1 . In the boiling operation the steam passes according to the hitherto employed method the same way during the first as during the second period, for instance, as regards the first spiral, the following way: F , a , A , a^1 , G .

The economy of the boiling is however, as stated above, to a high degree depending on the temperature of the escaping steam, and water of condensation, the latter being no doubt employed within the factory, although it can seldom be fully utilized.

In order to obtain a better economy in the boiling operation one now proceeds according to my present invention in the manner that the steam, mixed if necessary with water of condensation, is during the second period made to pass a longer way through the liquid so that it may act upon the liquid for a longer time. This result can be obtained in several manners, for instance by using the arrangement of the tubes shown in Fig. 2. According to this figure the coils may, by the use of connecting tubes and suitably located valves or other throttling arrangements, be coupled either in parallel so that the steam passes the same way as in Fig. 1, or in series so that the steam is made to pass through two coils before escaping through the outlet conduit. According to Fig. 2 six coils are used, namely H , I , J , K , L and M , which are by the conduits h , i , j , k , l and m respectively connected with the main steam supply conduit N . The outlet ends of the coils are by the conduits h^1 , i^1 , j^1 , k^1 , l^1 and m^1 connected with the main steam outlet conduit O . The conduits i and h^1 are connected with each other by a tube x . The conduit i is by a conduit 1 connected with the inlet end of the coil I , and the outlet end of coil H is by a conduit 2 connected with conduit h^1 . On both sides of the orifices of the conduits 1 and 2 there are located valves 3, 4 and 5, 6 respectively. In the same manner the conduit k is connected with the conduit j^1 by a connecting tube y . The conduit k is by a conduit 7 connected with the inlet end of coil K , and the outlet end of coil J is by the conduit 8 connected with the conduit j^1 . On each side of the orifices of the conduits 7 and 8 there are located valves 9, 10 and 11, 12 respectively. Moreover, the conduit m is connected with the conduit l^1 by a connecting tube z . The conduit m is by a conduit 13 connected with the inlet end of coil M , and the outlet end of the coil L is by a conduit 14 connected with the conduit l^1 . On each side of the orifices of the conduits 13 and 14 there are located valves or other throttling devices 15, 16 and 17, 18 respectively.

During the first period of the boiling operation (i. e. while the temperature is raised to about 100° to 105° C., these figures are only approximate and the invention is not limited to the same) when the consumption of steam is highest and the condensation in the coils most complete, the coils are in the ordinary manner coupled in parallel. The way of the steam will then through the first coil be the following: N , h , H , 2, h^1 , O and through the second coil: N , i , l , I , i^1 , O , and so on for the other coils. The valves 3, 9, 15, 6, 12 and 18 are then open, while the valves 4, 10, 16 and 5, 11, 17 are shut. Hereby the desired rapid "raising" of the boiling is obtained, without loss of steam. During the second period (from 100° or 105° C. and upward) when the boiling is getting "easier", at the same time as the condensation becomes less complete, the coils are coupled two and two in series, so that one, instead of six short coils, obtains three long ones. This coupling in series is obtained by shifting the said valves, so that the valves 3, 9, 15, 6, 12 and 18 are shut, while the valves 4, 10, 16, 5, 11 and 17 are opened. Consequently, during the second period the steam will pass the following way: N , h , H , 2, x , l , I , i^1 , O . Through the next two coils the steam passes as follows: N , j , J , 8, y , 7, K , k^1 , O , and through the last coils N , l , L , 14, z , 13, M , m^1 , O .

The result obtained by leading the steam in this manner during the second period is that the escaping steam has a considerably lower temperature in comparison with the corresponding period in the method hitherto employed. The higher the temperature then raises in the boiler the more the steam admission valve is throttled, and finally, when the maximum temperature (generally about 138° C.) has been reached, the steam admission valve can often be completely shut.

It is evident, that the arrangement according to Fig. 2, is shown and described as an example only and may, consequently, be varied within wide limits without departing from the scope of the present invention. Thus, it is not necessary to couple the coils in series two and two, but the coils may when this is convenient be coupled together three and three, four and four, etc. If for instance the coils are to be coupled three and three in series, the first and second, the second and third, the fourth and fifth, the fifth and sixth coils are, as is schematically illustrated in Fig. 3, combined with connecting tubes x^1 , x^2 , y^1 , y^2 in such a manner that the outlet end of the first coil H and the inlet end of the second coil I can be put in communication with each other by a connecting tube x^1 , and the outlet end of the second coil I can be put in connection with the inlet end of the third coil J by means of the next con-

necting tube x^2 , the outlet end of the last mentioned coil communicating with the main steam outlet conduit O. In the same manner the connecting tubes y^1 and y^2 are 5 combined with the coils K, L, M in the next group. As the valves are located and act in an analogous manner to that described in connection with Fig. 2 it ought to be unnecessary to repeat the description here.

10 The arrangement for coupling together the coils can of course be varied within wide limits. It is, thus, not necessary to use connecting tubes, for instance x , y , z in Fig. 2. This can be rendered possible by directly 15 coupling together the valves 4 and 5, 10 and 11, 16 and 17. This arrangement is schematically illustrated in Fig. 4 showing the lower part of a boiler in elevation. In order to avoid confusion the coils H, I, J, K, L, M within the boiler are not shown. It 20 is, however, easy to understand that the inlet end of the coil H is connected with the conduit h and the outlet end with the conduit h^1 , etc. During the first period the steam 25 will pass the following way through the first coil: N, h , H, h^1 , 6, O, the valves 4, 5 being shut and the valve 6 open. In an analogous manner the steam passes through each of the other coils. During the second period, when 30 the coils are coupled in series two and two, the steam will pass the following way through the first couple of coils: N, h , H, h^1 , 5, 4, i , I, i^1 , O, the valves 6 and 3 being shut and 4 and 5 being open, and so on for the 35 other couples of coils.

Fig. 5 schematically shows another arrangement, which is a combination of series and parallel coupling, the principal object of which is to reduce the number of 40 valves. The coils are here adapted to be coupled together in series three and three during the second period. During the first period the steam passes the same way as described in connection with Fig. 4, the valves 45 4 and 16 being then open and valve 10 shut. During the second period the valves 4 and 16 are shut and valve 10 open, and the steam then passes through the groups of coils as follows: N— h , i , j —H, I, J— h^1 , i^1 , j^1 —10— k , 50 l , m —K, L, M— h^1 , i^1 , m^1 —O.

To assure that the steam shall pass or be guided as desired, there may be used, instead of single principal valves, such as 4, 10 and 16, in Fig. 5, double principal valves, 55 and to locate testing valves between the latter, by the opening of which it is quite possible to ascertain the path of the steam at any time during the boiling operations, and to also ascertain whether the valves are 60 tight. Such an arrangement is schematically shown in Fig. 6, where the double principal valves are indicated at S_1 , S_2 , T_1 , T_2 and U_1 , U_2 . The testing valves (located between the double principal valves) are indicated at P_s , P_t and P_u respectively. Dur-

ing the first period, the valves S_1 and S_2 , U_1 and U_2 remain open, while valves T_1 and T_2 are closed, and it is then possible to make certain that the steam passes as desired, by opening testing valves P_s , P_t and P_u , in 70 which case steam will escape from P_s and P_u but not from P_t . During the second period, valves S_1 — S_2 and U_1 — U_2 remain shut, while T_1 and T_2 remain open. Upon opening the testing valves, steam will then escape from 75 P_t but not from P_s or P_u .

The present invention also comprises the above described arrangements which can be used in carrying out the method.

Finally it may be mentioned that I am 80 aware of the fact that, in sulfite cellulose factories with several boilers, it has been proposed to lead the steam escaping from a boiler into the coils of the next boiler for utilizing it there as heating steam instead 85 of fresh steam. According to this known system however, the coils in each boiler are in the ordinary manner coupled parallelly both during the first and the second period, and it is only the different boilers that are 90 coupled in series.

It is also known that one has tried to improve the economy of heat during the second period partly by throttling the main valve of the steam outlet conduit and partly by 95 locating at the said place an outlet for water of condensation.

Neither the one nor the other of these known systems anticipates the present invention as the latter is based on leading the 100 steam in one and the same boiler different ways during both the periods of the boiling operation, so that the steam is during each period utilized in the most favorable manner. This is obtained by so combining the 105 coils that they can during the first period be coupled parallelly and during the second period in series. In combination with this general arrangement one can of course within certain limits regulate the result by throttling to a suitable degree the main valve on the outlet side during the second period, and one may also, if desired, on said side locate 110 an outlet for water of condensation.

The advantages obtained by the present 115 invention as compared with the methods hitherto employed evidently consist in making possible as well a rapid raising of the température of the liquid to or nearly to the boiling point, as a better utilizing 120 than hitherto of the steam during the continuation of the boiling operation.

The expression "first period of the boiling operation" used in this specification includes 125 the raising of the temperature of the liquid from the ordinary temperature to or about the boiling point, and the expression "second period" includes the maintaining of the boiling temperature if the boiling takes place under ordinary pressure, or the raising 130

of the temperature above the boiling point and the maintaining of a desired temperature if the boiling takes place under an increased temperature.

5 Instead of steam any other heating agent may be employed.

Having now described my invention what I claim as new and desire to secure by Letters Patent is:

10 1. The method of indirectly boiling liquid, consisting in first leading a heating agent through each of a plurality of parallelly-coupled heating elements submerged in said liquid, and then connecting said heating elements in series and leading a heating agent through said serially-connected elements for a desired period of time.

20 2. The method of indirectly boiling liquid, consisting in first leading a heating agent through each of a plurality of parallelly-coupled heating elements submerged in said liquid, and then leading a heating agent through serially-connected heating elements submerged in said liquid.

25 3. The method of indirectly boiling liquid, consisting in first leading a heating agent through each of a plurality of parallelly-coupled heating elements submerged in said liquid, and until the temperature of said liquid is raised to about the boiling point, and then leading a heating agent through serially-connected heating elements submerged in said liquid, and raising the tem-

perature of the latter to any desired point above the boiling point.

35 4. The method of indirectly boiling liquid consisting in first leading steam together with water of condensation through each of a plurality of parallelly-coupled heating pipes submerged in said liquid, and until the temperature of said liquid is raised to about the boiling point, and thereafter connecting said heating pipes in series and leading steam together with water of condensation through said serially-connected pipes, 40 until the temperature of the liquid is raised to any desired point above the boiling point.

45 5. The method of indirectly boiling lye-liquid in the manufacture of sulfite cellulose, consisting in first leading a heating agent through each of a plurality of parallelly-coupled heating elements submerged in said liquid, and until the temperature has been raised to about 100-105° C., and then connecting said heating elements in series 50 and leading a heating agent through said serially-connected elements until the temperature of the liquid has been raised to about 138° C.

55 In testimony whereof I have signed my name to this specification in the presence of two subscribing witnesses.
